(12) **United States Design Patent** (10) Patent No.: **US D869,470 S**
Lim (45) Date of Patent: **** Dec. 10, 2019**

(54) **SSD STORAGE DEVICE**

(71) Applicant: **SAMSUNG ELECTRONICS CO., LTD.**, Suwon-si (KR)

(72) Inventor: **Gwangman Lim**, Seoul (KR)

(73) Assignee: **SAMSUNG ELECTRONICS CO., LTD.**, Suwon-si (KR)

(**) Term: **15 Years**

(21) Appl. No.: **29/665,720**

(22) Filed: **Oct. 5, 2018**

(30) **Foreign Application Priority Data**

(57) CLAIM

The ornamental design for an SSD storage device, as shown and described.

DESCRIPTION

FIG. 1 is a perspective view of an SSD storage device showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines and unshaded portions contained within broken lines depict unclaimed features of the SSD storage device that form no part of the design claim but are shown for illustrative purposes.
